UNITED STATES PATENT OFFICE

MARIN POPESCU, OF BUCHAREST, RUMANIA

LIFE PRESERVER

Application filed July 15, 1929. Serial No. 378,285.

This invention relates to life preservers that are supplied to passengers of ships, for their individual use in case of sinking of the vessel, and its principal object is to provide a reliable and efficient device for this purpose.

Heretofore, life preservers were designed to be worn by the person, usually about the chest, and these devices were generally stored away for use in the emergency. According to this invention the life preserver comprises a sort of marine vehicle, in which the passenger sits astride and is supported by efficient floats located at the front and rear of him, and when the life preserver is not in use it folds up completely to constitute a utilizable stool or steamer chair, thereby rendering a constant service and being normally in continuous control of and use by the passenger.

Other objects and advantages will herein-after appear.

In the accompanying drawings,—

Fig. 1 is a front elevation showing the life preserver of this invention as it appears when completely folded up to constitute a serviceable steamer chair.

Fig. 2 is a side elevation of the life preserver and chair shown in Fig. 1.

Fig. 3 is a front elevation of the life preserver shown in Fig. 1, as it appears when it is set up to serve its prime function of a life preserver.

Figs. 4 and 5 show details of the invention.

The life preserver comprises a chair 1 having a seat 2 and legs 3, and to the underside of seat 2 is secured an inverted saddle 4. To each pair of legs 3 is secured a pair of arms 5, to the terminals 6 of which is pivotally joined a float 7. Each cooperating pair of arms 5 is secured in place by means of a bolt-rod 8, having a head 9 and a threaded end 10, Fig. 4, passing clear through the two lower portions 11 of the legs 3, holes 12 of the arms 5, and a hole 13 of a flange 14 secured to one of the legs by screws 15. A wing-nut 16 threads over the rod-end 10 and against one of the end-portions 17 of one of the arms 5. In the leg-portion 11 to which the flange 14 is secured is formed a hole 18 in registry with the hole 13, and in

the hole 18 is located a helical spring 19 which is wound around the rod 8 and normally bears against the leg-portion 11 and the arm-portion 17. The flange 14 is provided with a series of holes 20, Figs. 4, 5, that are circularly arranged and concentric with its hole 13, and the arm-portion 17 carries a pair of pins 21 which may be inserted into any diametrically opposite pair of the holes 20, as shown in Fig. 4, to thereby set the arms 5 at any desired position angularly to the chair-legs 3. When the arms 5 are thus set and the wing-nut 16 is tightened, the bolt-head 9 is thereby drawn against its arm 5 and the wing-nut is forced against the arm portion 17 to retain the pins 21 in the holes 20, and the arms with the depending float 6 are in this manner retained and locked in the desired set position.

When the life preserver is not used to carry out its vital function, and is rather utilized as an ordinary steamer chair, its arms 5 are disposed as shown in Fig. 1 and its floats 7 are retained under the seat 2, and the nuts 16 are tightened to maintain these parts in the manner shown, with the floats neatly out of the way. If it is desired to retain a firmer hold of the floats against the legs 3, elastic bands 22 may be slipped over these parts in the manner shown in Figs. 1, 2.

When it is desired to utilize the life preserver in case of emergency, the chair 1 is inverted, the bands 22 are slipped off, and the wing-nuts 16 are unthreaded to permit the spring 19 to force away the arm-portion 17 and withdraw its pins 21 out of the locking holes 20 of the flange 14. The arms 5 may be then turned around to the outward position shown in Fig. 3 and the wing-nuts 16 may be tightened to retain them in that position, with the floats 7 disposed above the inverted chair. Thereupon the entire device may be placed or thrown into the water, in which case it will at once assume the position shown in Fig. 3 under any and all circumstances; viz, the chair 1 will be inverted and submerged and will be retained uprightly by the floats 7 which will be buoyed up in the level position shown at the approximate water level 23. The passenger

may then seat himself upon the saddle 4 and astride the chair seat 2, with the float 7 positioned in front of him and one at his rear, and be thereby safely and securely buoyed up in perfectly level state until rescue arrives. Should strong waves in any way tend to upset the life preserver and passenger the device will at once automatically right itself, due to the low centre of gravity of the chair and passenger, who is mostly submerged, and the pivotal relation of the arms 5 to the floats 7 at 6, which arms in this case act as free suspenders for the chair and passenger.

15 It will be noted that by means of setting the arms 5 at various angularities the extent of submergence of the chair 1 may be adjusted, either upwardly or downwardly relatively to the floats 7, and in this manner the 20 device may be set or adjusted to suit passengers of different sizes. Each float 7 is preferably made of sheet-metal and hollow, and preferably is made of a plurality of secured sections or chambers 7^a, so that if one chamber 25 is by any accident punctured the remaining chambers will continue to be operative and buoy up the preserver and passenger. One of the chambers 7^a may be preferably provided with a shutter 24 hinged at 25 and bolted at 26, whereby food or other vital articles may be enclosed therein and rendered available to the distressed passenger.

It will be evident that with this life preserver the distressed passenger may be seated in comfort and level position, and be safely and securely sustained until rescue arrives. When this life preserver is used as a chair it not only completely saves the space ordinarily reserved on board ships for 40 the special storage of life preservers, but by being constantly in the control of and utilized by the passenger it imparts to him such familiarity with its uses and purpose for the emergency that when the latter occurs he 45 finds himself able to manipulate it, and he is without the psychological fear ordinarily engendered when the distressed passenger is suddenly confronted with the problem of donning, what appears to him, a strange life 50 preserving contrivance.

The chair may be so constructed that the normal weight of its seat will create a low centre of gravity which will automatically dispose the chair-part of the life preserver in 55 its required inverted position shown in Fig. 3 when thrown into the water, but if required such automatic disposition of the chair and preserver may be insured by inserting a counter-weight 27 consisting of metal into the 60 seat structure.

Variations may be resorted to within the scope of the invention, and portions of the invention may be used without others.

Having thus described my invention, I 65 claim:—

1. A life preserver comprising a chair adapted to be submerged in inverted state, the inverted seat of said chair adapted to receive a person in sitting position, and a pair of oppositely disposed floats located at 70 the upper end of said inverted chair and being joined to the chair.

2. A life preserver comprising a chair adapted to be submerged in inverted state, the inverted seat of said chair adapted to receive a person in sitting position, a pair of oppositely disposed floats located at the upper end of said inverted chair, each of said floats being pivoted to arms, and said arms being joined to the chair.

3. A life preserver comprising a chair adapted to be submerged in inverted state, the inverted seat of said chair adapted to receive a person in sitting position, a pair of oppositely disposed floats located at the upper end of said inverted chair and being joined to the chair, and each of said floats comprising a plurality of independent chambers.

4. A life preserver comprising a chair adapted to be submerged in inverted state, the inverted seat of said chair adapted to receive a person in sitting position, a pair of oppositely disposed floats located at the upper end of said inverted chair and being joined to the chair, each of said floats comprising a plurality of independent chambers, and one of said chambers being adapted to contain food and having a shutter for opening and closing it.

5. A life preserver comprising a chair adapted to be submerged in inverted state, the inverted seat of said chair adapted to receive a person in sitting position, a pair of oppositely disposed floats located at the upper end of said inverted chair and being joined to the chair, and the inverted side of said seat having a saddle like structure to receive the person in astride sitting position.

6. A life preserver comprising a chair adapted to be submerged in inverted state, the inverted seat of said chair adapted to receive a person in astride sitting position, a pair of oppositely disposed floats located at the upper end of said inverted chair and being joined to the chair, and one of said floats being located in front of the person and the other at the rear of the person.

7. A life preserver comprising a chair adapted to be submerged in inverted state, the inverted seat of said chair adapted to receive a person in sitting position, a pair of oppositely disposed floats located at the upper end of said inverted chair and being joined to the chair, and said seat being weighted to insure the disposition of the chair in inverted state and the said upward relative location of said floats.

8. A life preserver comprising a chair

- adapted to be submerged in inverted state, the inverted seat of said chair adapted to receive a person in sitting position, a pair of oppositely disposed floats located at the upper end of said inverted chair and being joined to the chair, said seat being weighted to insure the disposition of the chair in inverted state and said upward relative location of said floats, the inverted side of said seat
- 5 having a saddle like structure to receive the person in astride sitting position, each of said floats being pivoted to arms, said arms being joined to the chair, and one of said floats being located in front of the person and the other at the rear of the person.
- 10 9. A life preserver comprising a chair adapted to be submerged in inverted state, the inverted seat of said chair adapted to receive a person in sitting position, a pair of oppositely disposed floats located at the upper end of said inverted chair and being joined to the chair, said seat being weighted to insure the disposition of the chair in inverted state and the said upward relative location of said floats, the inverted side of said seat having a saddle like structure to receive the person in astride sitting position, each of said floats being pivoted to arms, said arms being joined to the chair, one of said floats being located in front of the person and the other at the rear of the person, and each of said floats comprising a plurality of independent chambers.
- 15 10. A life preserver comprising a chair adapted to be submerged in inverted state, the inverted seat of said chair adapted to receive a person in sitting position, a pair of oppositely disposed floats located at the upper end of said inverted chair and being joined to the chair, said seat being weighted to insure the disposition of the chair in inverted state and the said upward relative location of said floats, the inverted side of said seat having a saddle like structure to receive the person in astride sitting position, each of said floats being pivoted to arms, said arms being joined to the chair, one of said floats being located in front of the person and the other at the rear of the person, each of said floats comprising a plurality of independent chambers, and one of said chambers being adapted to contain food and having a shutter for opening and closing it.
- 20 11. A life preserver comprising a chair adapted to be submerged in inverted state, the inverted seat of said chair adapted to receive a person in sitting position, a pair of oppositely disposed floats located at the upper end of said inverted chair and being joined to the chair, and means to adjust the elevation of said floats relatively to said inverted chair.
- 25 12. A life preserver comprising a chair adapted to be submerged in inverted state, the inverted seat of said chair adapted to receive a person in sitting position, a pair of oppositely disposed floats located at the upper end of said inverted chair, each of said floats being pivoted to arms, said arms being joined to the chair, and means to release the joint of said arms and chair to permit disposal of the floats within the chair under its seat to convert the device to chair use when not acting as a life preserver.
- 30 13. A life preserver comprising a chair adapted to be submerged in inverted state, the inverted seat of said chair adapted to receive a person in sitting position, a pair of oppositely disposed floats located at the upper end of said inverted chair, each of said floats being pivoted to arms, said arms being joined to the chair, means to release the joint of said arms and chair to permit disposal of the floats within the chair under its seat to convert the device to chair use when not acting as a life preserver, and means to retain the floats and chair in said converted state.
- 35 14. A life preserver comprising a chair adapted to be submerged in inverted state, the inverted seat of said chair adapted to receive a person in sitting position, a pair of oppositely disposed floats located at the upper end of said inverted chair and being joined to the chair, and means to release the joint of said arms and chair to permit disposal of the floats within the chair under its seat to convert the device to chair use when not acting as a life preserver.
- 40 15. A life preserver comprising a chair adapted to be submerged in inverted state, the inverted seat of said chair adapted to receive a person in sitting position, a pair of oppositely disposed floats located at the upper end of said inverted chair and being joined to the chair, each of said floats being pivoted to arms, and each of said arms adapted to be joined to the chair at a plurality of places to adjust the elevation of said floats relatively to said inverted chair.
